DECANTER

Ernest L. Du Pree, Weston, Conn., assignor to Schenley Industries, Inc., New York, N. Y., a corporation of Delaware

Application December 7, 1955, Serial No. 39,195

Term of patent 14 years

(Cl. D58—6)

The two sides of the decanter not shown are the same as the side shown in Figure 2.

I claim:

The ornamental design for a decanter, as shown and described.
